Patented Dec. 19, 1922.

UNITED STATES PATENT OFFICE.

MALCOLM L. COSSITT, OF ALAMEDA, CALIFORNIA, ASSIGNOR TO MANIFOLD IMPRESSIONS CORPORATION, OF CARSON CITY, NEVADA, A CORPORATION OF NEVADA.

MANIFOLDING ATTACHMENT FOR TYPEWRITERS.

Application filed November 25, 1921. Serial No. 517,473.

To all whom it may concern:

Be it known that I, MALCOLM L. COSSITT, a citizen of the United States, residing at Alameda, in the county of Alameda and State of California, have invented certain new and useful Improvements in Manifolding Attachments for Typewriters, of which the following is a specification.

My invention relates, in general, to that class of manifolding devices for typewriters and similar typing machines, in which one or more manifolding ribbons are mounted upon the platen-carriage of the machine and are adapted to be moved into and out of functional position in the line of type impact.

In particular, my invention relates to a type of this class, in which the manifolding ribbon is carried by and between a pair of spaced arms mounted for swinging movement, whereby the ribbon is carried through an arcuate path to and from functional position; and, more especially it relates to a species of said type using a plurality of ribbons adapted for independent movement, such a form being disclosed in my pending application for patent, Serial Number 402876, filed August 11, 1920.

My invention consists in a novel means for moving the manifolding ribbon to and from functional position, and, in case of a plurality of ribbons, for selectively, independently moving them.

The object of my invention is to provide simple, effective, and readily operable means for this purpose, especially adapted for association with that type or form of manifolding attachments having the characteristics of the device shown in my application above referred to.

In illustrating and explaining my present invention, I shall necessarily show and describe portions of the general attachment heretofore disclosed in said application, but such portions will be readily distinguishable from the present invention, as will be seen from the descriptive matter and particularly from the claims hereunto appended.

In the accompanying drawings—

Fig. 1 is a top skeleton plan of a typewriter showing the general application thereto of my manifolding attachment.

Fig. 2 is a front elevation of one end of my attachment.

Fig. 3 is a sectional view on the line 3—3 of Fig. 2.

Fig. 4 is a perspective view of the selective ribbon-operating means and the means for moving the ribbon in the direction of its width, at each line spacing of the platen.

Fig. 5 is a longitudinal section of said means on the line 5—5 of Fig. 3.

Fig. 6 is a side view of the mutilated pinion for selectively operating the ribbon carrying arms.

Fig. 7 is a detail section showing the yieldable connection between the yoke of the line-spacing ribbon-adjustment and the crank movement.

Fig. 8 is a view showing the three positions of the ribbon under the line spacing movement.

Fig. 9 is an end view of my attachment, the three ribbons being shown in position out of use.

Fig. 10 is a similar view showing one of the ribbons moved down about its own axis, to a position adjacent the line of type impact.

Fig. 11 is a similar view showing the ribbon moved down about the crank axis into the line of type impact.

Fig. 12 is a view showing all three ribbons moved down to their functional position in the line of type impact.

Fig. 13 is a perspective view showing the selective mutilated pinion movement, if it be found advisable to have said device duplicated at each end of the attachment.

In Fig. 1, the numeral 50 is the frame of a typewriter; 51 its keys, 52 its main inking ribbon, 53 the ribbon spools, 54 the index pointer and 55 the paper guide apron.

1 is the platen of the typewriter mounted on its carriage 1' and having the hand wheel 1'' and the spacing ratchet 2. 3 is a standard secured on the platen-carriage of the machine beyond the end of the platen, one at each end, as in Fig. 1.

In the head of one of these standards, say the right hand one, is journaled a shaft 4, Figs. 2, 3, 4 and 5, having a thumb-wheel 5, Figs. 1 and 2 for turning it. To the inner end of the shaft is fixed a crank member 6, the free end of which carries a rod 7, which extends parallel with, and above and back of the platen to the other end of said platen

where it is carried by a crank-member 6', Fig. 13, similar to 6, which member is carried by rotatable shaft 4' similar to 4 journaled in the standard 3, secured upon the 5 platen-carriage beyond that end of the platen.

Upon the rod 7 are carried the sleeves 8, 8' and 8'', Figs. 2, 4 and 5. These are nested, and each is independently rotatable, the innermost, 8, being rotatable on the rod 7, the next, 8', rotatable on sleeve 8, and the outermost, 8'', rotatable on sleeve 8'. There may be any suitable number of these sleeves, here shown as three, for example.

15 On the end of the innermost sleeve 8 is fixed an arm 9; on the end of the middle sleeve is fixed an arm 9'; and on the end of the outermost sleeve is fixed an arm 9''. Similar arms, are similarly carried by the 20 other ends of the sleeves. Fig. 1.

25 Detachably and reversibly mounted upon and extending between each pair of arms is a manifolding ribbon 10, 10' and 10'' respectively. Figs. 1 and 2. The base of each arm is formed with a toothed segment 11, 11' and 11'' respectively. These are clearly seen in Fig. 4. The shaft 4 is hollow and within it is journaled a shaft 12, on the outer end of which is fixed a thumb 30 wheel 13—Figs. 1 and 2. The inner end of this shaft carries a mutilated pinion, the face of which is provided with tooth sections in parallel planes, but in successive arcs. Figs. 4 and 6. One section, indicated 35 by 14, engages the toothed segment 11 of the arm 9; the next, 14', engages the segment 11' of the arm 9', while the last, 14'', engages the segment 11'' of the arm 9''. It will be noted that these tooth sections of 40 the pinion do not follow each other immediately, a space occurring between the end of one and the beginning of the next. See Fig. 6. This is for a purpose to be presently made clear.

45 It will now be seen that by turning the shaft 12, by means of its thumb wheel 13, through a partial rotation, the pair of arms 9 with their ribbon 10 may be swung with their sleeve 8 as an axis; and by continuing 50 the movement of the thumb wheel 13 in the same direction, the pair of arms 9' with their ribbon 10' may be swung with their sleeve 8' as an axis; and finally by continuing the movement of the thumb wheel 55 pair of arms 9'' with their ribbon 10'' may be moved.

60 Thus the ribbons may be independently selected to be thrown into and out of use either singly or collectively according to whether one or plural copies are desired, and, if the mounted position of the ribbons were of such a nature as to make their paths sufficiently concentric with the platen, nothing further would be needed to carry them 65 fully down, without interference with any

of the parts of the machine, into functional position in the line of type impact. But, as fully described in my previous application above mentioned, the mounting of the ribbons is best in a position requiring a distorted path, in which they first move down through an arc on one center, and make their final movement to functional position through an arc on another center, in order to avoid the platen and get in behind the 70 index pointer of the machine and to lie between it and the platen. I have herein again provided for these two centers, through the instrumentality of the crank members 6 and 6', shafts 4 and 4' and thumb 75 wheel 5. When, therefore, a ribbon, say 10 has been moved down about its sleeve 8, as an axis, to a position, as shown in Fig. 10, which is not quite that of its final functional position, said movement being accomplished by operating the thumb wheel shaft 12, then by operating the thumb wheel shaft 4, the ribbon will, through the action of the crank members 6 and 6' which move the sleeve carrying rod 7 bodily forward, descend to its final position as shown in Fig. 11, moving about the shafts 4 and 4' as an axis. This operation about two centers is in effect like that disclosed and claimed in my previous application, but the structure 95 herein adapts itself to a change in the means for securing further results now to be explained.

90 In one of the standards 3 is fitted an inwardly projecting stud 15', Figs. 2, 3, 4 and 5, upon which is rotatably mounted a cam 15 carrying on one side a pinion 16, which meshes with the spacing ratchet 2 of the platen 1. A yoke 17 embraces the cam 15, and the head 17' of the yoke is pivotally 100 mounted upon the shaft 4, so that the yoke may rock. In the yoke head 17' are made two sockets 18, Fig. 7, spaced apart by a distance in degree of arc equal to that between the limits of movement of the crank member 6. The crank member 6 is formed with an extension 6'' in which is made a socket containing a spring 19 and a locking ball 20, which latter is pressed by the spring into the sockets 18 of the yoke head 17'. Figs. 5 and 7. The effect of this arrangement is two-fold. One is that it effectively holds the ribbon in or out of its final functional position, by releasably locking the crank member 6 at the limits of its 115 arc of oscillation. The other is that it provides for the automatic change of position of the ribbon when in functional place with respect to its width, at each line-spacing of the platen. When the platen is line-spaced, its ratchet 2 engaging the pinion 16 causes the cam 15 to move the yoke 17. Since the yoke is connected with the shaft 4, through the spring pressed ball 20 of the crank extension 6'', the crank is itself 120 125 130

5 moved with the effect of slightly moving the rod 7 and thus changing the position of the ribbon with respect to its width. According to the contour of the cam, the yoke 5 may be successively moved in one direction a number of times, as indicated in Fig. 8, and then moved back again, thus presenting the ribbon to the blows of the type over practically its entire width. At the same 10 time, the spring-pressed ball connection is not such as will prevent the manual manipulation of the shaft 4 to swing the crank to carry the ribbon into and out of functional position. The object in leaving a 15 space between the end of one tooth section, say 14 of the arm operating pinion and the beginning of the next, say 14', is to prevent the tooth segment 11' of the arm not wanted, say arm 9', from reaching engagement with its own tooth section 14' of the 20 pinion during the bodily movement of the rod 7 due to the throw of the crank-member, when moving the ribbon of arm 9 down to its final position. Thus no ribbon is affected until its predecessor has been fully 25 adjusted.

A brief résumé of the operation will now give a more complete understanding of the present invention. When out of use, all the 30 ribbons are elevated as shown in Figs. 1, 2 and 9. If but one is required for use, say the foremost ribbon 10, the thumb wheel 13 is turned clock-wise, through a part revolution. This, through the shaft 12, the tooth 35 section 14 of the mutilated pinion, and the tooth-segment 11 of the arm 9 will swing said ribbon 10 down through an arc terminating in the position shown in Fig. 10. Then the thumb-wheel 5 is turned partly to throw 40 the crank-member 6 forwardly and downwardly, thereby carrying the rod 7 down and moving the ribbon 10 down to final position, as in Fig. 11. In this final movement the spring pressed ball 20 moves from the 45 upper locking socket 18 to the lower socket, as in Fig. 7, and holds the parts with sufficient firmness. If two ribbons are wanted, the thumb-wheel 13 is turned through two arcs of its revolution, with the effect of carrying 50 down two ribbons to their first position, and then the throw of the crank member 6 will cause both to reach and be locked in functional position. So, too, with three or more ribbons, as in Fig. 12. Meanwhile, when 55 the ribbons are in use, their position laterally will be changed at each line spacing of the platen, through the cam and yoke connection.

I claim:—

60 1. In a manifolding attachment for typewriters, the combination of a manifolding ribbon; carrying means for said ribbon, pivotally mounted on the platen-carriage of the machine and adapted to swing said ribbon 65 in an arcuate path; a rotatable operating

shaft; and means operated by said shaft to swing the ribbon carrying means, comprising intermeshing gears.

2. In a manifolding attachment for typewriters, the combination of a plurality of 70 independent, manifolding ribbons; independent carrying means for each of said ribbons, pivotally mounted on the platen-carriage of the machine; a rotatable operating shaft; and means operated by said shaft 75 for independently, selectively swinging the ribbon-carrying means.

3. In a manifolding attachment for typewriters, the combination of a plurality of 80 independent, manifolding ribbons; independent carrying means for each of said ribbons, pivotally mounted on the platen-carriage of the machine; a rotatable operating shaft; and means operated by said shaft 85 for independently, selectively swinging the ribbon-carrying means comprising successively engaging gears.

4. In a manifolding attachment for typewriters, the combination of a plurality of 90 independent, manifolding ribbons; a plurality of independent pairs of connected spaced ribbon-carrying arms pivotally mounted on the platen carriage of the machine; a rotatable operating shaft; and means, associated with said shaft and said arms, for 95 independently, successively swinging the pairs of ribbon-carrying arms by a unidirectional rotation of the shaft.

5. In a manifolding attachment for typewriters, the combination of a plurality of 100 independent, manifolding ribbons; a plurality of independent pairs of connected spaced ribbon-carrying arms pivotally mounted on the platen carriage of the machine; a rotatable operating shaft; and means, associated with said shaft and said arms, for 105 independently, successively swinging the pairs of ribbon-carrying arms by a unidirectional rotation of the shaft comprising successively engaging gears.

6. In a manifolding attachment for typewriters, the combination of a plurality of 110 independent, manifolding ribbons; a plurality of independent pairs of connected, spaced, ribbon carrying arms pivotally mounted on the platen-carriage of the machine; a rotatable operating shaft; a tooth-segment on the base of an arm of each pair of arms; and a mutilated pinion on the operating shaft having peripheral, successive, tooth-sections in parallel planes, each adapted to engage the tooth-segment of its corresponding arm, to independently, successively swing the pairs of ribbon-carrying arms.

7. In a manifolding attachment for typewriters, the combination of a pair of standards adapted to be secured upon the platen-carriage of the machine; a rod supported by said standards; a series of concentrically nested independently rotatable sleeves 120

mounted on said rod; a pair of spaced arms carried by each sleeve; a manifolding ribbon carried by each pair of arms; an operating shaft rotatably mounted in one of said standards; and means actuated by the rotation of said shaft for independently, selectively swinging each pair of arms.

8. In a manifolding attachment for typewriters, the combination of a pair of standards adapted to be secured upon the platen-carriage of the machine; a rod supported by said standards; a series of concentrically nested independently rotatable sleeves mounted on said rod; a pair of spaced arms carried by each sleeve; a manifolding ribbon carried by each pair of arms; an operating shaft rotatably mounted in one of said standards; and means actuated by the rotation of said shaft for independently, selectively swinging each pair of arms comprising successively engaging gears.

9. In a manifolding attachment for typewriters, the combination of a pair of standards adapted to be secured upon the platen-carriage of the machine; a rod supported by said standards; a series of concentrically nested independently rotatable sleeves mounted on said rod; a pair of spaced arms carried by each sleeve; a manifolding ribbon carried by each pair of arms; an operating shaft rotatably mounted in one of said standards; and means actuated by the rotation of said shaft for independently, selectively swinging each pair of arms, comprising a tooth-segment on the base of an arm of each pair; and a mutilated pinion on the operating shaft having peripheral, successive tooth-sections in parallel planes, each adapted to engage the tooth-segment of its corresponding arm.

10. In a manifolding attachment for typewriters, the combination of a pair of standards adapted to be secured upon the platen-carriage of the machine, a rotatable shaft mounted in each of said standards; a crank member carried by each of said shafts; a rod carried by and between said crank members; a series of concentrically nested, independently rotatable sleeves mounted on said rod; a pair of spaced arms carried by each sleeve; a manifolding ribbon carried by each pair of arms; a second rotatable shaft carried by and concentric with one of the crank-carrying shafts; and means associated with the second shaft and with the ribbon carrying arms for independently, selectively swinging said arms by the rotation of said second shaft.

11. In a manifolding attachment for typewriters, the combination of a pair of standards adapted to be secured upon the platen-carriage of the machine; a rotatable shaft mounted in each of said standards; a crank member carried by each of said shafts; a rod carried by and between said

crank members; a series of concentrically nested, independently rotatable sleeves mounted on said rod; a pair of spaced arms carried by each sleeve; a manifolding ribbon carried by each pair of arms; a second rotatable shaft carried by and concentric with one of the crank-carrying shafts; and means associated with the second shaft and with the ribbon carrying arms for independently, selectively swinging said arms by the rotation of said second shaft, comprising a tooth-segment on the base of each arm; and a mutilated pinion on the second shaft having peripheral successive tooth-sections in parallel planes, each adapted to engage the tooth-segment of its corresponding arm.

12. In a manifolding attachment for typewriters, the combination of a pair of standards adapted to be secured upon the platen-carriage of the machine; a rotatable shaft mounted in each of said standards; a crank member carried by each of said shafts; a rod carried by and between said crank members; a series of concentrically nested, independently rotatable sleeves mounted on said rod; a pair of spaced arms carried by each sleeve; a manifolding ribbon carried by each pair of arms; a second rotatable shaft carried by and concentric with one of the crank-carrying shafts; and means associated with the second shaft and with the ribbon carrying arms for independently, selectively swinging said arms by the rotation of said second shaft, comprising a tooth-segment on the base of each arm; and a mutilated pinion on the second shaft having peripheral successive tooth-sections in parallel planes, each adapted to engage the tooth-segment of its corresponding arm, and said pinion tooth sections following each other with a space intervening to avoid engagement during the swing of the crank member.

13. In a manifolding attachment for typewriters, and in combination with the platen and the line spacing ratchet thereof; a pair of standards adapted to be secured upon the platen-carriage of the machine, a rotatable shaft mounted in each of said standards; a crank member carried by each shaft; a rotatable member supported by and between said crank members; an arm carried by said rotatable member one at each end; a manifolding ribbon carried by said arms; a second rotatable shaft mounted within and extending through one of the crank-carrying shafts; means associated with the second shaft and the ribbon-carrying arm for swinging said arm with its rotatable member as an axis; a pinion and cam carried by one of the standards, said pinion engaging the line spacing ratchet of the platen; a yoke embracing said cam, said yoke having a head journaled on the crank-carrying shaft and provided with spaced

sockets; a socketed extension of the crank member; and a spring controlled ball carried in said extension and adapted to releasably engage the sockets in the head of the

5 yoke for the purpose described.

14. A multi-copy attachment for typewriters and the like comprising pairs of levers pivotally mounted upon said typewriter; copying elements mounted between 10 one set of ends of each pair of levers; and a rotative element directly connected to the opposite ends of said levers and arranged to actuate said levers in pairs to move the copying elements opposite the point of contact of 15 the type bars of said typewriter with the platen thereof.

15. A multi-copy attachment for typewriters and the like comprising pairs of levers pivotally mounted upon said typewriter; copying elements detachably mounted between one set of ends of each pair of levers; and a rotative element arranged to directly engage the opposite ends of said levers and to actuate the same to success-

sively move said levers to bring the copying elements thereon opposite the point of contact of the type bars of said typewriter with the platen thereof.

16. A multi-copy attachment for typewriters and the like comprising pairs of 25 levers pivotally mounted upon said typewriter; copying elements detachably and reversibly mounted between one set of ends 30 of each pair of levers; and a rotative element arranged to directly engage the opposite ends of said levers and to actuate the same to successively move pairs of said levers to successively bring the copying elements into and out of operative position 35 opposite a line of contact between the 40 point of contact of the type bars of said typewriter and the platen thereof and to normally retain said pairs of levers in and out of said operative position.

In testimony whereof I have signed my 45 name to this specification.

MALCOLM L. COSSITT.
